UNITED STATES PATENT OFFICE

2,645,276

JOINT STRUCTURE FOR METAL TUBING

Earl C. Booth, Columbus, Ind., assignor to Arvin Industries, Inc., a corporation of Indiana

Application September 1, 1949, Serial No. 113,550

3 Claims. (Cl. 155—196)

1

This invention relates to furniture and other articles constructed of metal tubing and more particularly to a structure embodying cylindrical legs and one or more tubular stretchers extending between and secured to such legs. It is an object of the invention to provide for such a structure a stretcher which will serve both to interconnect the legs between which it extends and also to provide feet for such legs.

In carrying out the invention, a length of metal tubing of which a stretcher is to be formed is cut obliquely at its ends, the planes of the two cuts converging upwardly with respect to the position which the stretcher is to occupy in the finished article. The metal along the upper portion of each cut end is next displaced outwardly of the tube to form a short semi-cylindrical flange having an internal diameter approximating the external diameter of the leg with which the finished stretcher is to be connected. A cylindrical punch is then inserted through such cylindrical flange transversely of the tube-axis and, in cooperation with an appropriate die, forms the end of the tube into an upwardly opening, leg-receiving socket the lower end of which is offset downwardly from the lowermost point of the tube-wall.

The accompanying drawing illustrates the invention.

Fig. 1 is a side elevation of a collapsible chair which shows, by way of example, the manner in which the invention is embodied in an article of furniture; Figs. 2 and 3 are sectional views illustrating the two sets of dies employed in the formation of a stretcher-end; Fig. 4 is a fragmental front elevation of a leg and stretcher in assembled relation; Fig. 5 is a section on the line 5—5 of Fig. 4; and Figs. 6 and 7 are fragmental elevations showing the stretcher in two intermediate stages of its function.

The chair shown in Fig. 1, which is illustrated merely as an example of articles of furniture and other structures in which my invention may be incorporated, embodies a pair of side frames each comprising a front leg 10, a rear leg 11, and a stretcher 12 which rigidly interconnects the two legs. Both legs and the stretcher are formed of metal tubing. The chair as a whole forms the subject matter of my prior United States Letters Patent No. 2,608,240, granted August 26, 1952, and constitutes no part of the present invention.

In the following description of the manner in which each stretcher is formed, it is assumed for the sake of convenience that during its forma-

2

tion the stretcher occupies the same position about its axis as it does in the finished chair.

The length of tubing from which each stretcher is to be formed is cut off obliquely so that its two end faces 13 (Fig. 6) converge upwardly. The angle which the plane of each end face 13 makes with the axis of the tubing is desirably somewhat less than 45°. As a first step in the formation of the stretcher, the tubing is brought into association with a divided die 15 having a cylindrical recess which, when the die is closed, provides exterior support for the tubing over all portions of the outer surface thereof lying to the left and below the chain line 14 of Fig. 6. With the tubing so supported in the die 15 a punch 16 is then inserted axially into it. Such punch has a pilot portion 17 and a laterally projecting shoulder 18 which, in plan, is semi-circular in shape and has a diameter approximately equal to the diameter of the legs 10 and 11. As the punch 16 is forced home, that portion of the tubing 12 which lies above and to the right of the broken line 14 and which is unsupported by the die 15 is distorted to conform to the nose of the shoulder 18. This bent metal forms a short flange 19 (Fig. 7) which is generally semi-cylindrical in plan and which has an interior diameter approximately equal to the outer diameter of the leg which it is to receive.

After the flange 19 has been formed on one end of the stretcher, the die 15 is opened, the stretcher is reversed and a similar flange 19 is formed on the other end.

For the next step in the formation of the stretcher, its ends are successively subjected to the action of the die combination illustrated in Fig. 3. The die 21 shown in Fig. 3 has a shallow, upwardly opening cylindrical recess 22 and, extending laterally from a point above each recess, a semi-cylindrical groove which provides support for the stretcher 12 over the lower half of its circumference. A punch 24 aligned with the recess 22 has an external diameter approximately equal to the diameter of each of the legs 10 and 11. With the punch 24 elevated, the stretcher 12 is placed in the die 21 in such a position that the descending punch will engage the inner face of the flange 19. If desired, the punch 24 when elevated may be so disposed that its lower end is only slightly above the axis of the stretcher, in which event the flange 19 may be seated against the side of the punch in order to locate the stretcher 12 in proper position both axially of itself and angularly about its axis. When the punch 24 is lowered, the end of the tub-

ing is formed to provide an upwardly opening socket adapted to receive a leg having a diameter equal to that of the punch 24. As the bottom of such socket is offset downwardly below the lowermost point of the body of the stretcher, the socket forms a foot when the stretcher is embodied in an article of furniture.

After one end of the stretcher is formed to provide a socket, the stretcher is reversed in the die 21, and a socket is formed on the other end. In assembling the finished stretcher with the legs 10 and 11, the lower ends of the legs are placed in the socket and secured therein preferably by brazing.

If desired, each of the sockets may be provided in its bottom with an opening adapted to permit the escape of any paint which may enter the interior of the tubular members while they are being painted as well as to permit the escape of any water which may enter the tubular members when the articles of furniture in which they are embodied are in use. When such openings are desired they may be formed by a punch 26 as an incident to formation of each socket. If such openings are employed, I have found it desirable to form them so that their peripheries will be deflected inwardly, as shown in Fig. 3, to constitute a flange which will form the lower portion of the socket into a trap for any melted spelter entering the socket during the brazing of the legs in place.

In the finished article of furniture, the sockets on the ends of each stretcher serve not only to interconnect the stretcher and legs but also to provide the feet necessary to provide adequate bearing area for legs formed of tubing. Cost of manufacture is reduced, as the foot is formed in the same operation by which the stretcher-end is brought into conformity with the leg, and it is therefore unnecessary to provide and assemble a foot as a separate article of manufacture.

I claim as my invention:

1. In a fabricated structure, a pair of spaced

legs and a stretcher interconnecting them, said stretcher comprising a metal tube deformed at each end to provide an integral socket projecting laterally of the tube in one direction to form a foot and opening laterally of the tube in the opposite direction, the ends of said legs being received and secured in said sockets, each socket having a bottom overlapping the lower end of the associated leg.

2. In a fabricated structure, a pair of spaced legs and a stretcher interconnecting them, said stretcher comprising a metal tube deformed at one end to provide an integral socket projecting laterally of the tube in one direction to form a foot and opening laterally of the tube in the opposite direction, the end of one of said legs being received and secured in said socket, each socket having a bottom overlapping the lower end of the associated leg.

3. The invention set forth in claim 2 with the addition that the leg received in said socket is tubular, the bottom of said socket being provided with an opening connecting with the interior of the tubular leg.

EARL C. BOOTH.
